UNITED STATES PATENT OFFICE

2,162,370

COMMUNICATION SYSTEM

Richard H. Campbell, Racine, Wis., assignor to
 Webster Electric Company, Racine, Wis., a corporation of Wisconsin

Application July 19, 1937, Serial No. 154,345

13 Claims. (Cl. 179—1)

The present invention relates to intercommunication systems, and particularly to systems comprising a single central or master station and one or more remote stations.

5 It is an object of this invention to provide an intercommunication system with an improved arrangement for producing a signal at the central station whenever an operator at a remote station desires to communicate with the central station.

10 A further object of the invention is to provide an intercommunication system with signaling means enabling an operator at the central station to determine at a glance which of the remote stations desires to communicate with the central station, and in which certain interstation conductors are used both for transmission of speech and for actuating the signaling means.

15 A further object of the invention is to provide a multiple station intercommunication system with signaling means including a single audible signal and a plurality of visual signals, the audible signal being actuatable from all remote stations and a predetermined one of the visual signals being actuatable from any particular remote station.

20 A further object of the invention is to provide a communication system of the type described in which both the audible and visual signals are actuated through the same interstation conductors.

25 A further object of the invention is to provide a multiple station intercommunication system comprising direct current speech transmitting means and alternating current signal actuating means, in which common conductors are utilized in a non-interfering manner for transmitting speech and actuating the signals.

30 Other objects and advantages of the present invention will become apparent from the ensuing description, in the course of which reference is had to the accompanying drawing, the single figure of which is a schematic circuit diagram of one embodiment of the invention.

35 Referring now to the drawing, the reference numeral 10 designates voice receiving and transmitting means, such as a dynamic loudspeaker of the type employing a permanent magnet and a voice coil suspended in the field thereof, located at a station from which the communication system is to be controlled. This station may be aptly termed either a master or central station, and hereinafter will be referred to as a central station.

40 Loudspeaker units 11, similar in all respects to unit 10, are located at one or more remote stations

between which and the control station it is desired to communicate.

45 The fluctuations in current produced in speaker units when acting as transmitters are amplified by an amplifier 12 of any suitable type comprising one or more stages of amplification and supplied with power from an alternating current source through a rectifier. The amplifier may be provided with volume control as well as a switch for connecting it to a suitable source of power, but since these elements, as well as the amplifier itself, may be of any well known construction, they are not illustrated or described in great detail herein. For present purposes, it is deemed sufficient to state that the amplifier comprises input and output transformer coils 13 and 14, respectively, each having one terminal thereof connected to a common conductor 15 which is grounded as indicated at 16.

50 A selectively operable master switch 17 is provided at the central station for connecting the speaker unit 10 thereto to either the output or input of the amplifier, and simultaneously conditioning the remote speaker units 11 for connection to the input or output of the amplifier, through selector switches 18, also located at the central station and corresponding in number to the number of remote stations.

55 The selector switches 18 not only serve the purpose of connecting the remote stations to the master switch 17, but also provide means adapted to cooperate with control switches 19 at the remote stations for actuating an audible signal, such as a buzzer 20, and visual signals 20' at the central station. The signal actuating circuits are so arranged that whenever an operator at a remote station wishes to communicate with the central station, he displaces the switch 19 from its normal position to a displaced position thereby to actuate the buzzer 20 and the visual signal means 20' associated with that station. The details of this circuit arrangement are described hereinafter.

60 The master switch 17 is biased by suitable means, such as a spring, to a normal position in which the speaker unit 10 is connected to the output coil 14 and the speaker units 11 are conditioned for connection to the input of the amplifier by means of the selector switch 18. Switch 17 is a double pole double throw switch connected for operation as a reversing switch. The switch blades 21 and 22 thereof are connected by conductors 23 and 24 to the voice coil of speaker unit 10 and to a plurality of branch conductors 25, 55

respectively. The branch conductors 25 are in turn connected to the normally open switch blades 26 of the selector switches 18. The selector switches 18 are also double pole double throw switches, the other blades 27 of which are normally closed switches connected by conductor 28 to the common conductor 15.

Returning now to the construction of the reversing switch and its circuit connections, it may be noted that the ungrounded terminal of the input coil 13 is connected by a conductor 31 to the interconnected contacts 32 and 33 of the switch, and that the output coil 14 is similarly connected by a conductor 34 to the interconnected contacts 35 and 36.

In the normal position of the master switch 17 the voice coil associated with speaker unit 10 is connected across the output of the amplifier through conductor 34, switch blade 22 in engagement with contact 35, and conductor 23 leading to one terminal of the voice coil, the other terminal of which is connected by a conductor 37 to the common conductor 15. In the displaced position of the switch, the voice coil is connected across the input of the amplifier through conductor 31, switch blades 22 in engagement with contact 32, and conductor 23 and through the conductor 37.

The selector switches 18 are biased into a normal position in which the system is conditioned for the actuation of the audible and visual signal means at the central station from any one of the remote stations. In this position the switch blades 26 thereof are in circuit opening position and the switch blades 27 are in engagement with contacts 41. The contacts 41 are connected by conductors 42 to low impedance solenoid windings 43 adapted when energized to actuate the visual signals 20' into positions in which they may be observed by the operator at the central station. The visual signals may conveniently consist of an armature 44 that must be manually returned to a normal position in which the signal is not in view. Thus, whenever the winding 43 is energized, the signal 20' is brought into view and remains there until the operator at the central station returns it to its normal position. The solenoid windings 43 are connected by conductors 45 to interstation conductors 46 leading to the switch blades 47 of the control switches 19 at the various remote stations. Conductors 46 are also connected to contacts 48 adapted to be engaged by switch blades 26 of the selector switches 18 in their displaced position.

The switch blades 47 of the control switches are adapted normally to establish circuits from conductors 46 to conductors 49 connected to the terminals of the voice coils of the remote speaker units, the other terminals of which are connected by a common conductor 50 to the common conductor 15.

The switch blades 47 are operable to a displaced position in which they engage contacts 51 connected by a conductor 52 to the buzzer 20. The other terminal of the buzzer is connected to the low voltage secondary winding of a transformer 53, the primary winding of which is connected to any suitable source of alternating current power which may be and preferably is the source supplying power to the amplifier. The other terminal of the secondary winding of the transformer is connected by a conductor 54 to the common conductor 15.

In operation, the amplifier 12 is supplied with power from any suitable source and is normally

in an operative condition so that speech may be transmitted from the central station to the remote stations or vice versa at all times. Likewise, the transformer 53 is connected to a suitable source of power to provide a source of low voltage for the signal actuating portion of the system.

The system is normally conditioned for actuation of the signal means at the central station from any one of the remote stations by reason of the fact that the selector switches 18 at the central station are biased into a position in which the switch blade 26 is in circuit breaking position and the blade 27 connects the relay winding 43 to one side of the secondary winding 15 of transformer 53 through conductors 28 and 15. Thus whenever the operator at a remote station desires to communicate with the master station it is only necessary for him to operate the switch blade 41 from its normal to its displaced position wherein it engages contact 51 to complete a circuit through the relay winding and buzzer. The circuit is completed through conductors 45, 46, switch blade 47, in engagement with contact 51, conductor 52, to the buzzer 20 and thence directly to the terminal of the secondary winding. Thereupon the buzzer 20 gives an audible signal and the relay winding 43 actuates its armature 44 to position the visual signal means associated therewith so that it can be observed by the operator at the central station.

The audible signal apprises the operator at the central station that one of the remote stations is calling and the visual signal apprises him of the particular remote station calling. Thus the necessity of the operator remaining at his post at all times is avoided.

If the operator at the central station wishes to respond to the call, he operates the selector switch 18, corresponding to the station calling, into its displaced position in which the switch blade 26 thereof is in engagement with contact 48 and the switch blade 27 in its open position. The opening of switch blade 27 disrupts the signal circuit from the selected remote station and the closure of switch 26 establishes a circuit from the speaker unit at the selected remote station to the input of the amplifier through the switches 47 and 17 in their normal positions. The circuit extends from the input coil of the amplifier to the voice coil of the remote speaker 11 through conductor 31, switch blade 21 in engagement with contact 33, conductor 24, branch conductor 25, switch blade 26 in engagement with contact 48, conductor 46, and switch blade 47 in engagement with conductor 49.

At this time the speaker unit 10 at the central station is connected across the output coil of the amplifier through a circuit that has been described previously and which includes conductor 34 and the switch blade 22 in engagement with contact 35.

When the operator at the central station wishes to talk to the operator at the remote station selected, he simply operates the master switch 17 to its displaced position at which time the speaker unit at the central station is connected to the input coil of the amplifier and the speaker unit 11 at the remote station to the output coil of the amplifier.

When the conversation is completed the operator at the central station simply releases the master switch 17 and the selector switch 18, thereby conditioning the system for actuation of the signal means at the remote station 11 when

ever the operator at the latter station desires to communicate with the central station.

In view of the fact that each of the remote stations has its own visual signal means and 5 selector switch at the central station, an operator at the remote station may indicate a desire to communicate with the central station while the central station is in communication with another of the remote stations. Furthermore, 10 since the switch blades 26 of the various selector switches 18 are in parallel, the central station can be placed in communication with all the remote stations simultaneously by manipulation of the selector switches into their displaced positions.

The system described above is adapted for use with any number of remote stations and it should be apparent to those skilled in the art that the selector switch 18 need not be one which is biased 20 into a predetermined position. Its operation may be controlled entirely by the operator at the central station. In the event that it is not biased to a predetermined position, it should be manually returned to its normal position upon 25 completion of a conversation.

The system is adapted particularly for use in locations where it is not convenient for an operator to be stationed at the central station at all times. An example of this type of use is 30 furnished by tool rooms or warehouses in which there is only a single attendant. The attendant may leave the location of the speaker unit and if any one calls him in his absence, he is apprised of the fact by the visual signal means, as well as 35 by the audible signal.

Another advantage of the system resides in the fact that it may be operated from a single source of alternating current power because there is no interference between the direct current 40 communication system and the alternating current signal actuating circuit. Interference is eliminated by disrupting the signal circuit whenever communication is established by operation of switch blades 47 and 27.

While only a single embodiment of the invention has been described, it is not contemplated that the principles of the invention should be limited thereto. Other modifications thereof 50 will suggest themselves to those skilled in the art and it is contemplated that the present invention is limited only by the claims appended hereto.

What I claim as new and wish to secure by United States Letters Patent is:

1. In an intercommunication system, the combination including a pair of remotely located stations, means including plural position switches at one station for controlling a communication circuit and a signal circuit between the two 60 stations, said switches being operable to a position in which the communication circuit is open and the signal circuit conditioned for closure, and means including a control switch at the other station normally closing the communication circuit thereat and operable to a displaced position for completing said signal circuit.

2. In an intercommunication system, the combination including a pair of remotely located stations, voice receiving and transmitting means 70 at each station, means including plural position switches at one station for controlling communication and signal circuits between the two stations, said switches normally occupying positions in which the communication circuit is open and the signal circuit closed, and means including a

switch normally connecting the voice receiving and transmitting means at the other station to the communication circuit for completing the signal circuit.

3. In an intercommunication system, the combination including a pair of remotely located stations, voice receiving and transmitting means at each station, signal means at one station, means including an interstation conductor and a switch at said one station for controlling communication and signal circuits, a control switch at the other station for controlling said circuits, said first mentioned switch being operable to a predetermined position to disconnect the voice receiving and transmitting means at said station from said conductor and to connect the signal means thereto, and said control switch normally completing a connection from an interstation conductor to the voice receiving and transmitting means at said other station and operable to complete a signal actuating circuit through said first mentioned switch when the latter is in said predetermined position.

4. In an intercommunicating system, the combination including a pair of remotely located stations, speech receiving and transmitting means at each station, signal means at one station, means including an interstation conductor and a pair of simultaneously operable switches at said one station for controlling communication and signal circuits extending in part through said conductor, a control switch at the other station for additionally controlling said circuits, said first mentioned switches being biased into a normal position in which one of 30 said pair of switches opens the connection of the communication circuit to the interstation conductor and the other closes the signal circuit and operable into a displaced position to complete the communication circuit and open the signal circuit, and said control switch being biased into a normal position to complete the connection of the voice receiving and transmitting means to the interstation conductor and operable to a displaced position to complete the signal circuit, 40 whereby the system is conditioned for actuation of the signal means at the central station upon operation of said control switch to its displaced position and for transmission of speech upon operation of said first mentioned switch to its 45 displaced position.

5. In an intercommunication system, the combination including, a central station, a plurality of remote stations, means including a number of plural position selector switches at the central station equal to the number of remote stations for controlling communication and signal circuits between the central station and the remote stations, said switches being operable to a position in which the communication circuit is open and the signal circuit conditioned for closure, and means including control switches normally closing communication circuits at the remote stations for completing the signal circuit through the selector switch associated with that station.

6. In an intercommunication system, the combination including, a central station, a plurality of remote stations, voice receiving and transmitting means at each station, an audible signal and a number of visual signals equal to the number of remote stations at the central station, means including a number of plural position selector switches equal to the number of remote stations at the central station for controlling communication and signal circuits between the central sta- 70

tion and the remote stations, said switches being operable to a position in which the communication circuits to the associated remote station are open and the circuits to the audible signal and visual signals are conditioned for closure, and means including a control switch at each remote station normally connecting the voice receiving and transmitting means at that station to the communication circuit for completing the circuit 10 to the audible signal and the visual signal associated with that station.

7. In an intercommunication system, the combination including, a central station, a plurality of remote stations, loudspeaker units at each station, signal means at the central station, means including a number of interstation conductors and a similar number of double pole switches at the central station for controlling communication and signal circuits extending in part through said 15 conductors, a control switch at each remote station for additionally controlling said circuits, said first mentioned switches being biased to a normal position in which one blade of each of said double pole switches opens the connection of the communication circuit to the interstation conductor and the other closes the signal circuit and operable to a displaced position to complete the communication circuit and open the signal circuit, and said control switches being biased into a 20 normal position to complete the connection of the loudspeaker units to said interstation conductor and operable to a displaced position to complete the signal circuit, whereby the system is conditioned for actuation of the signal means at the 25 central station upon operation of any one of said control switches to its displaced position and for communication to the remote station upon operation of any one of the double pole switches to its displaced position.

8. In an intercommunication system, the combination including, a central station, a plurality of remote stations, loudspeaker units at each station, an audible signal and a number of visual signals equal to the number of remote stations 30 at the central station, said signals being electrically actuatable and connected in series parallel relationship whereby the audible signal is actuated whenever any one of the visual signals is actuated, means including a number of double pole switches and interstation conductors equal to the number of remote stations at the central station for controlling communication and signal circuits extending in part through said conductors, a control switch at each remote station 35 for additionally controlling the communication and signal circuits, said first mentioned switches being biased to a normal position in which one blade of each opens the connection of the communication circuit to the interstation conductor and the other closes the parallel branch circuit including the visual signal and operable to close the communication circuit and open the signal circuit, and said control switches being biased into a normal position to complete the connection 40 of the loudspeaker units at the remote stations to said interstation conductor and operable to a displaced position to complete the connection of the signal circuit through the audible signal and the associated visual signal to a source of power.

9. In an intercommunication system, the combination including, a pair of remotely located stations, loudspeaker units at each station, an amplifier, a double pole double throw switch at a first station for connecting the speaker unit at 45 that station to the output and input of the ampli-

fier and simultaneously connecting a communication circuit extending to the second station to the input and output of the amplifier, said communication circuit including a normally open switch at the first station and a normally closed 5 switch at the second station, signal means at the central station, and means including a normally closed switch operable simultaneously with said normally open switch and a circuit adapted to be closed by the normally closed switch at the second station in its communication-circuit opening position for actuating said signal means.

10. In an intercommunication system, the combination including, a central station, a plurality of remote stations, loudspeaker units at each station, an amplifier, a double pole double throw switch at the central station for connecting the speaker unit at that station to the output and input of the amplifier and simultaneously connecting a communication circuit to the remote stations to the input and output of the amplifier, said communication circuit comprising a common conductor and a branch interstation circuit leading therefrom to each remote station, each of said interstation circuits comprising a normally 25 open switch at the central station and a normally closed two position control switch at the remote station, signal means at the central station, and means including a switch at the central station operable conjointly with the last mentioned 30 switch at the central station and cooperating with the control switch at the remote station in its other position for actuating said signal means.

11. A multiple station intercommunication system, including in combination, a central station, 35 a plurality of remote stations, a loudspeaker at each station, an amplifier, signal means at the central station, means for selectively connecting the loudspeaker thereto to the output and input of the amplifier and simultaneously connecting 40 the loudspeakers at the remote stations to the input and output of the amplifier, said means including a reversing switch and a selector switch for each remote station located at the central station, and a control switch located at each remote station, said selector switches normally breaking a circuit from the reversing switch to the control switch associated therewith, and said control switch normally completing a circuit from its associated selector switch to the speaker, and 45 means for actuating said signal means from all said remote stations, said means including a plurality of parallel circuits adapted to be completed through a selector switch in its normal position and a control switch in its displaced position. 55

12. An intercommunication system, including in combination, a central station, a plurality of remote stations, loudspeakers at each station, an amplifier having input and output terminals, a master switch at the central station for connecting the speaker thereto to the output and input and simultaneously conditioning the speakers at the remote stations for connection to the input and output of said amplifier, said switch being biased to connect the speaker at the central station 60 to the output and to condition the remote speakers for connection to the input of the amplifier, a plurality of selector switches at the central station operable from a normal position to a second position for selectively completing the connection 65 of the respective speakers at the remote stations to said master switch, said last mentioned switches being biased to their normal positions, a switch at each remote station normally connecting the speaker thereto to the second position of 70 75

the selector switch associated with that station and operable to a second position, a single audible signal and a plurality of visual signal means at the central station, and means including a circuit completed through a selector switch in its normal position and an associated switch at the remote station in its second position for actuating said audible signal and a predetermined one of said visual signals.

10 13. In an intercommunication system, the combination including a pair of remotely located sta-

tions, means including a pair of simultaneously operable switches at one station for controlling respectively a communication circuit and a signal circuit between the two stations, said switches being operable to a position in which the communication circuit is open and the signal circuit conditioned for closure, and means including a control switch at the other station for completing said signal circuit.

RICHARD H. CAMPBELL. 10
